(57) **CLAIM**

The ornamental design for an archery bow grip, as shown and described.

DESCRIPTION

FIG. 1 is a front-right angled view of the archery bow grip; FIG. 2 is a right-side view thereof; FIG. 3 is a left-side view thereof; FIG. 4 is a back view thereof; FIG. 5 is a front view thereof; FIG. 6 is a top view thereof; and, FIG. 7 is a bottom view thereof. The broken lines in the Figures indicate unclaimed portions of the device and are for illustrative purposes only. The broken lines form no portion of the claimed design.
